UNITED STATES PATENT OFFICE.

JAMES M. DORMON, OF ARCADIA, LOUISIANA.

PLOW.

SPECIFICATION forming part of Letters Patent No. 240,579, dated April 26, 1881.
Application filed June 26, 1880. (No model.)

To all whom it may concern:

Be it known that I, JAMES M. DORMON, a resident of the town of Arcadia, parish of Bienville, and State of Louisiana, have invented a certain new and useful Improvement in Plows; and I do hereby declare the following to be a full, clear, and correct description of the same, reference being had to the annexed drawings, making a part of this specification.

10 This invention relates more particularly to that class of plows known as "turning-plows."

It consists in forming the blades in two pieces, and in so constructing the parts that they may readily and rigidly be secured together.

15 The object in view is to enable the points to be removed, should the same become broken or too badly worn to perform good work, and to provide for the substitution of new points 20 in lieu of those removed.

My invention will be more readily understood by referring to the accompanying drawings, whereon—

Figure 1 is a front view, partially in perspective, of the plow. Fig. 2 is a sectional view, showing the lap and connections, taken through the line $x-x$ of Fig. 1. Fig. 3 is a rear view of the plow. Fig. 4 is a perspective view of the plow-point section. Fig. 5 is a perspective view of the upper portion of the plow, showing the lapping of the pieces. Fig. 6 is a perspective view of the mold-board section.

25 In the annexed drawings, forming a part of this specification, the letter A represents the mold-board section, and B represents the plow-point section. The section A is formed with an offset, d , affording a seat for the upper portion of the plow-point section, and is also formed with two openings or holes to receive 30 the bolt and stud, hereinafter described. The lower edge, e , of the mold-board section is tapering or beveled, as seen in Fig. 6 of the draw-

ings. The plow-point section B is formed, near its upper end, with an opening to receive a bolt, and with a screw-threaded stud, D, arranged 45 immediately below, as shown in Fig. 4 of the drawings. The lower edge of this plow-point section is turned up, forming a V-shaped groove, h , as seen in Fig. 4, to receive and form a seat for the lower beveled edge of the mold-board section, as shown in cross-section in Fig. 2 of the drawings. The sections A and B are adjusted and secured together in their relative positions by the bolt C and screw-threaded stud D, as fully seen in Figs. 1, 2, and 3 of the 55 drawings. The parts of the sections which are placed in contact with one another are rolled or otherwise constructed so as to fit snugly, and to present on either side a perfectly even and smooth surface.

60 The introduction of my invention will reduce the labor and cost of keeping plows in repair, owing to the fact that it dispenses entirely with the welding and resetting or reshaping of the same.

65 The points are very easily and cheaply made, and their application to the main parts readily and securely effected.

Having described my invention, what I claim as new, and desire to secure by Letters Patent, is—

70 The combination of the plow-point section B, formed with the V-shaped groove at the base, and the mold-board section A, having its lower edge beveled, said section B adapted to 75 overlap the section A, substantially as shown and described.

In testimony whereof I have hereunto signed my name.

JAMES M. DORMON.

In presence of—

D. E. BROWN,
B. W. GLOVER.
